(57) **CLAIM**

The ornamental design for a camera fence clamp, as shown and described.

DESCRIPTION

FIG. 1 is a front view of a camera fence clamp showing my new design;

FIG. 2 is a right view thereof;

FIG. 3 is a top view thereof;

FIG. 4 is a bottom view thereof;

FIG. 5 is a back view thereof;

FIG. 6 is a bottom, back, and left perspective view thereof;

FIG. 7 is a top, front, and left perspective view thereof; and,

FIG. 8 is a perspective view of the camera fence clamp in position clamped on a fence.

The items represented in dashed lines are not part of the claimed design and serve as environmental elements only.
